INVENTOR

George F. A. Ochs,
Youngstown,
ATTORNEY.

UNITED STATES PATENT OFFICE.

GEORGE F. A. OCHS, OF NEWARK, NEW JERSEY.

RAILROAD-TIE.

1,350,381.

Specification of Letters Patent. Patented Aug. 24, 1920.

Application filed October 17, 1919. Serial No. 331,262.

To all whom it may concern:

Be it known that I, GEORGE F. A. OCHS, a citizen of the United States, and a resident of Newark, county of Essex, and State of New Jersey, have invented certain new and useful Improvements in Railroad-Ties, of which the following is a specification.

This invention relates to an improved railroad tie which is preferably made of metal and which is adapted to securely hold the rail in position, but also have the proper weight as required in a tie of this kind.

The invention is an improvement over my prior Patent No. 1,208,630, issued Dec. 12, 1916. In the prior patent the rail was fastened directly to the tie. In the present construction the improvement lies in inserts which are held in the tie when the rail is put down, and which are adapted to receive clamping means, such as spikes or the like, to secure the rail in position.

The inserts are designed to receive a spike in a curved passage or recess, which inserts can be replaced if they are damaged or incomplete. In the manufacture of the ties, if by any reason there is a faulty making of the passage which receives the spike, when the tie is one piece the whole tie is wasted, whereas in the present construction this is corrected in so far as only the insert would need to be replaced. Furthermore, the present type of tie is more easily manufactured.

The invention is illustrated in the accompanying drawing, in which Figure 1 is partly a side view and partly a section of my improved tie, showing two rails mounted thereon, the center rib being shown in elevation. Fig. 2 is a top view of the construction shown in Fig. 1, with the left hand rail and the spikes of that rail omitted. Fig. 3 is a perspective view showing several of the parts separated to more clearly illustrate their construction, and Fig. 4 is a perspective view of a spike.

The tie 10 is made preferably of metal, and to secure a proper degree of resiliency and still give the tie sufficient weight, I prefer to make it with longitudinal ribs 11 and the cross-ribs 12. Flanking each rail position I provide recesses 13, into which the inserts 14 are placed, the inserts being adapted to be held in place by the rail and also adapted to receive the holding means, such as a spike, to hold the rail down.

In the form shown, the removable inserts

are provided on their outer edges with a nose 15, which nose projects underneath the ledge 16 at the edge of the recess, the nose of the insert, as at 17, bearing on the body portion of the tie and being held against any downward movement, the remainder of the insert resting on a cut-out position of the center rib. The inner end of each insert is provided with a lip 18 which rests on a ledge 19 at the inner end of the recess 13.

I prefer to make the top of the tie and the top of the inserts flush when the parts are assembled, so that the base 20 of the rail 21 rests on the top of the tie and also on the inner ends of the inserts and they are thus securely held in position, the inner edges of the inserts being held down by the rail, and the outer edges being held down by the overlapping ledge 16.

I prefer to dispose the parts so that one of the cross-ribs 12 is under the rail position to give more stability to the rail at this point, although this arrangement is not essential.

Means are provided for fastening the rail to the inserts, in the form shown this comprising spikes 22, the heads of which are adapted to rest against the base of the rail, and the spikes are driven into the curved passage or channel 23, which is preferably made square, as at 24, at a point adjacent to the base of the rail, the channel passing out at the top of the insert, as at 25, this outlet being preferably made round, whereby the whole channel is U-shaped, which permits of its easy manufacture, and the core necessary in making the channel is easily withdrawn.

I prefer to give each spike a coat of tin to prevent corroding or rusting, and the channel or hole in the insert is preferably filled with lubricating grease, and the round end 25 can be closed with a plug to keep out water.

In practice I make the spikes with considerable taper, so that the pointed end easily conforms, under blows, to the shape of the opening or channel into which it is placed, and at the same time it can be removed by the use of a punch bar or similar tool when it is desired to remove the spike.

I claim:

1. A railroad tie having recesses flanking the rail position, readily removable inserts in said recesses and partly covered by the

rail, said inserts having means therewith for securing them to the rail, the inserts and tie having coacting means for holding the inserts in place.

5. A railroad tie having a recess therein, an insert adapted to fit in the recess with one end of the insert held by the tie against upward movement, a rail resting on the other end of the insert, and means for securing the rail to the insert.

10. A railroad tie having a recess therein, an insert adapted to fit in the recess with one end of the insert held by the tie against upward movement, a rail resting on the 15 other end of the insert, the insert having a curved channel therein, and a spike in the channel and engaging the rail.

15. A railroad tie having a recess therein,

an insert adapted to fit in the recess with one end of the insert held by the tie 20 against upward movement, a rail resting on the other end of the insert, the insert having a U-shaped channel, and a spike in the channel and clamping the rail to the insert.

25

5. A railroad tie having a recess in the top, one end of the recess having an overhang and the other end a ledge, an insert with a nose to go under the overhang and a lip to rest on the ledge, and a rail resting 30 on the top of the tie and the top of the lip.

In testimony that I claim the foregoing, I have hereto set my hand, this 15th day of October, 1919.

GEORGE F. A. OCHS.
